(57) **CLAIM**

The ornamental design for a watch strap, as shown and described.

DESCRIPTION

FIG. 1 is a rear and left perspective view of a first embodiment of a watch strap showing my new design;
FIG. 2 is a rear and left perspective view of the watch strap of FIG. 1 in a first unfolded state;
FIG. 3 is a rear and left perspective view of the watch strap of FIG. 1 in a second unfolded state;
FIG. 4 is a front, right and top perspective view of the watch strap of FIG. 1 in a third unfolded state, wherein a body and a movable part are detached;
FIG. 5 is a front view thereof;
FIG. 6 is a rear view thereof;
FIG. 7 is a left side view thereof;
FIG. 8 is a right side view thereof;
FIG. 9 is a top plan view thereof;
FIG. 10 is a bottom plan view thereof;
FIG. 11 is a rear and left perspective view of a second embodiment of a watch strap showing my new design;
FIG. 12 is a rear and left perspective view of the watch strap of FIG. 1 in a first unfolded state;
FIG. 13 is a rear and left perspective view of the watch strap of FIG. 1 in a second unfolded state;
FIG. 14 is a front, right and top perspective view of the watch strap of FIG. 1 in a third unfolded state, wherein a body and a movable part are detached;
FIG. 15 is a front view thereof;
FIG. 16 is a rear view thereof;
FIG. 17 is a left side view thereof;
FIG. 18 is a right side view thereof;
FIG. 19 is a top plan view thereof;
FIG. 20 is a bottom plan view thereof;
FIG. 21 is a rear and left perspective view of a third embodiment of a watch strap showing my new design;
FIG. 22 is a rear and left perspective view of the watch strap of FIG. 1 in a first unfolded state;
FIG. 23 is a rear and left perspective view of the watch strap of FIG. 1 in a second unfolded state;
FIG. 24 is a front, right and top perspective view of the watch strap of FIG. 1 in a third unfolded state, wherein a body and a movable part are detached;
FIG. 25 is a front view thereof;
FIG. 26 is a rear view thereof;
FIG. 27 is a left side view thereof;
(Continued)

FIG. 28 is a right side view thereof;
 FIG. 29 is a top plan view thereof;
 FIG. 30 is a bottom plan view thereof;
 FIG. 31 is a rear and left perspective view of a fourth embodiment of a watch strap showing my new design;
 FIG. 32 is a rear and left perspective view of the watch strap of FIG. 1 in a first unfolded state;
 FIG. 33 is a rear and left perspective view of the watch strap of FIG. 1 in a second unfolded state;
 FIG. 34 is a front, right and top perspective view of the watch strap of FIG. 1 in a third unfolded state, wherein a body and a movable part are detached;
 FIG. 35 is a front view thereof;
 FIG. 36 is a rear view thereof;
 FIG. 37 is a left side view thereof;
 FIG. 38 is a right side view thereof;
 FIG. 39 is a top plan view thereof; and,
 FIG. 40 is a bottom plan view thereof.
